John Syrcher

United States Patent Office.

JOHN SYRCHER, OF BUFFALO, NEW YORK.

Letters Patent No. 60,961, dated January 1, 1867.

WHEEL TOY.

The Schedule referred to in these Letters Patent and making part of the same.

TO THE COMMISSIONER OF PATENTS:

Be it known that I, JOHN SYRCHER, of the city of Buffalo, and State of New York, have invented a new and useful improvement in Toy Wheels; and I do hereby declare that the following is a full and exact description thereof, reference being had to the accompanying drawings, making part of this specification, in which—

Figure 1 is a plan view of the edge of the wheel; and

Figure 2 a central section in a plane at right angles with the axis.

Like letters designate corresponding parts in both figures.

My invention consists in the manner hereinafter described of attaching the string to the toy known as the "bandalore."

In the drawings, A represents the groove cut in the circumference of the wheel, leaving a hub or axle, D, for the string F to wind upon; C is the aperture in the centre of the wheel, and B a small hole through the hub to this central opening for the passage of the string. E is a block of India rubber or other elastic material, (preferably of the form shown in fig. 2,) to which the string is attached by tying or otherwise, and then inserted in the opening, C. If desired, the ends of the rubber may be fastened to the wheel in any suitable manner, the string alone, however, being sufficient to keep it in its place. H is a ring at the outer end of the string for the insertion of the finger, G, in operating the toy, which also serves as a stop to prevent the end of the string being drawn in the groove A in winding. The toy is operated in the usual manner, by first winding the string around the hub D, in the groove A, and then by letting go of the wheel the string unwinds causing the wheel to revolve; the momentum which it acquires by the peculiar jerking motion given to the string causing it to alternately revolve in one direction, and then in the opposite. As the string becomes unwound, the strain upon the end attached to the rubber compresses it, when its recoil or elasticity imparts a greater impetus to the wheel as its motion is being reversed, which increases the motion and attractiveness of the toy.

What I claim as my invention, and desire to secure by Letters Patent, is—

Attaching the string F to the India-rubber or other elastic block E, in the manner and for the purpose described.

JOHN SYRCHER.
